JOINTER FENCE ADJUSTMENT

William B. Boice, Toledo, Ohio, assignor to Boice-Crane Company, Toledo, Ohio, a corporation of Ohio

Application August 10, 1948, Serial No. 43,394

3 Claims. (Cl. 144—253)

1

This invention relates to definite positioning as to location and inclination of guide or stop means, more particularly as to a plane surface.

This invention has utility when incorporated with a deck or table top, especially as having a rotary cutting tool protruding upwardly therefrom. As a jointer fence, a guide face may be positioned in a desired relation laterally of the tool for an elected spacing, with control for definitely fixing an angularity for the fence face as to the top. There is accordingly provided hereunder quick range for accurate setting of the fence, adapted especially for woodworking, artificial lumber, and compositions of a general character responsive to special edge dressings or configurations.

Referring to the drawings:

Fig. 1 is a partly broken away front elevation, shown in dotted lines, of a power-operated jointer machine tool unit base and deck, having, as shown in full lines, a fence therefor with adjustment controls;

Fig. 2 is a view from the left of Fig. 1, of a responsive mounting for the jointer fence at the end thereof remote from the calibrated or definite setting selectable controls;

Fig. 3 is an elevation from the right of Fig. 1, showing the table-directed slide plate and largely broken away as to a cooperating tilt plate, and at a stop position for the guide at 135° from the plane of the table top;

Fig. 4 shows the full tilt plate in front of the slide plate, and here tilted to 90° from the plane of the table top; and

Fig. 5 is on a still larger scale, in section along the axial region of the clamp controls, from the left of Fig. 4, with parts broken away and showing the stop for the tilt plate engaging the underside of the table top for the fence face to be set at 45° from the plane of the table top as extending from under the overhanging fence.

A pedestal or base 1 has thereon a mounting 2 for locating a table flat top or deck 3 having an opening 4 centrally therein. As a power tool, a motor 5 may have a rotary cutting tool 6 in a desired protruding relation at the opening 4 in its effective working range above the top 3.

A jointer fence body 7 is shown with a plane face 8 downwardly terminating in an edge portion 9 of slight clearance and parallel to the deck 3. The edge 9 in its extent toward the opening 4, adjacent the opening 4 has a lug 10 as a rest to contact the deck 3 with a clearance 11 across the region of the tool 6 with an edge 12 therefrom of somewhat more clearance as to

the deck 3 than the edge 9. The fence body 7 from adjacent the end of the edge 12 as away from the clearance 11, has a projection 13 carrying a trunnion 14 to enter a bearing 15 of a downwardly inclined slotted link 16. At an edge 17 of and fixed with the table top 3 is an externally threaded pin 18 extending thru slot 19 of the link 16. Upon the pin 18 toward the link 16 is a washer 20. A knurled handle or knob 21 may be set to act as a clamp for the link 16 for the range of control positions to be set for the face 8 of the fence member or body 7.

The table top 3 opposite to and parallel with the edge 17, has a track 22. The track 22 has open ends and is open outward. Insertable in the track 22 is a slide plate 23 having on its outer upwardly extending face a pair of lugs or bosses 24. More centrally fixed with the plate 23 and protruding between the bosses 24 is an interior smooth bore sleeve 25 having intermediate its extent an externally threaded portion 26.

Fixed by screws 27 with the fence body 7 is a tilt plate 28. Plate edge 29 is anchored by the screws 27 to be in the plane of the fence face 8. From the plate edge 29 and shown as at 135° spacing therefrom is a plate edge 30. In the vicinity of the convergence of these edges 29, 30, is an axis region 31 as the active location for the cutter 6. From this region 31 as a center is an arc slot 32 in the tilt plate 28.

The arc slot 32 at its root or back portion has a ledge region 33 of slight clearance as to the external diameter of the hollow stem or sleeve 25 and as a groove extends to open ends beyond the slot 32 for the full arc of extent of the tilt plate 28. In this open ended way portion 33 at the back of the tilt plate 28, may ride the bosses or lugs 24. A bounding ledge or rim 34 surrounds the open face of the slot 32 and provides a seat for the washer 20 of the clamp lock in the coaction of the knurled knob 21 with the threaded portion 26 of the stem 25 in pulling the slide plate 23 into holding relation with the tilt plate 28 at the elected tilt position for the fence face 8.

Positioning the slide plate

Spaced upwardly from the bottom of the track 22 to align with the bore of the sleeve 25 is a slot 34' having a countersunk entrance portion 35. A rectangular head 36 has a projecting rib 37 as a key to ride in the entrance portion 35. A bolt or stem 38 fixed with the head 36 extending thru the bore of the sleeve 25 and, as protruding therefrom in the knob 21, has an externally

threaded portion 39 in an axial recess 40 of the knob 21. A cap nut 41 with an angularly extending wrench handle 42, may be turned, into binding or independent clamp coaction with end 43 of the sleeve 25. There is thus effected a positive clamping or locking of the slide plate 23 in the track 22 of the table. This action is independent of any setting or release of the knob 21 as to the tilt plate 28. In practice this means that the plate 23 may be set to vary the spacing of the fence face 8 as to the cutting tool 6. Then, with such setting or location determined, the rise plane for the fence face 8 may be additionally and separately elected and clamped thru the operation of the knob 21. During these angularly placings for the face 8 over the range desired, the setting as determined by the wrench handle 42 in clamping the plate 23 may be left undisturbed.

Tilt plate special stops.

From the axis 31 a radial line 43 at approximately 45° from the direction of the edge 29 has a bolt 44 protruding from outer arc face 45 of the tilt plate 28. The bolt 44 is a pivot parallel to and spaced from the line 43 toward the edge 29. The bolt 44 fixedly clamps an arm or offset 46 against a fixed pin 47 on the side of the arm 46 away from the line 43. Thru the free end of the arm 46 and in a direction perpendicular to the line 43 is an externally threaded stem 48 which may be locked at adjusted position by a nut 49. At this adjusted projection for the stem 48, end face 50 of the stem 48 is brought just to the direction of the line 43. This means that as the face 50 is swung down to strike the top of the table 3, the face 29 extends away from the axis 31 to have the fence face 8 make an angle of 135° opening from the top of the table 3. This is a fixed stop determining the maximum back or opening swing or tilt for the jointer fence face 8.

The tilt plate 28, at 90° from the face or edge 29, at a radial line 51 has a second bolt 44 parallel thereto and mounting a swing arm 46 frictionally held by a spring washer 52 when the free end of this arm 46 is not overhanging but along the face 45. At this position, the stop at the radial line 43 may be effective. However, with the arm 46 swung outward, that is, to overhang laterally from the face 45, in proximity to the radial line 51, the end face 50 of its stem 48 as adjustably set by the lock nut 49 therefor, in striking the top of the table 3, is with such top coincident with the line 51. This positions the fence face 8 to rise vertically from the table 3.

A third radial line 53 at 135° from the edge 29, in its extent outward from the tilt plate outer arc face 45 has clearway toward the line 51 and at the other side of such line 53 there is a third bolt 44 frictionally, by a spring washer 52, mounting a swing arm 46 so that it may be moved into out of use position along the face 45, or swung to have its free end outward and ride against the pin 47 for its stop face 50 of its stem 48 to be against under side 54 of the table 3. (Fig. 5) to bring the face or edge 29 to 45° up angle from the table top 3.

Tilt plate selective stops

Fixed with the slide plate 23 is a pointer 54, preferably set to indicate 0° when the swingable stop face 50 is at the line 51 to coincide with the top of the table 3. That is, at such location the fence face 8 and the edge 29 extend vertically, or are at 90° or perpendicular as to the

plane of the table top 3. 0° location is on a scale 55 of the tilt plate 28 outside of and adjacent to the arc slot 32. As shown, the scale 55 is of 90° overall extent, being 45° each way from the 0° marking or notation. The graduations along the scale 55 may be with such refinement as desired, even down to degrees, minutes and seconds. However, on the showing the markings are 15°. In the practice hereunder involving the special stops for 45°, 90° and 135°, it is desirable that the operator, as the fence body 1 comes to rest, then set the knobs 21 at the link 16 and the slot 32 into clamp-effecting position, for in the locating of the fence these knobs had each been released. As heretofore brought out, only the clamping from the knobs 21 should be released for the angle setting, and the fixing of the slide plate 23 thru the wrench handle 42 clamp is holding.

Upon occasion arising for jointer fence setting at a special angle as selective beyond or differing from the special stops as identified, it is in order for the operator to use the scale 55. For instance, it be desired to have the angle between the table top 3 and the fence face 8 to be 105°, the stop in the region of the line 51 is swung away from offset position to rest along the arc face 45 and thus be clear of the table 3. The tilt plate 28 is rocked clockwise (Fig. 4) to the first 15° graduation above the 0° notation as determined by the pointer 54. Then the knobs 21 are turned to clamping position, thus locking the plate 28 against any shifting as to the slide plate 23 or the table 3. This locking is independent of the special stops, and is a direct clamping fixing the fence body 1 at the readily rocked position in shifting effected thru a hand hold 56. The cap nut 41 against the sleeve end 43 has fixed the plate 23 with the table track 22. The knobs 21 thru the washers 20 grip the link 16 and the plate 28.

What is claimed and it is desired to secure by Letters Patent is:

1. In a jointer having a table, an adjustable fence movable and tiltable over said table, a track at one end of said table, a tilt plate attached to one end of said fence, a slide plate cooperating with said track and attached to said tilt plate, the improvement comprising: separate co-axial simultaneously operable clamping means for said slide plate and said tilt plate, respectively, swingable stop means for limiting the tilt of said tilt plate, a pivot bearing for mounting said stop means on the periphery of said tilt plate, said bearing having an axis substantially radial to the axis of tilt of said tilt plate, and a radially extending stop pin on the periphery of said tilt plate co-acting to limit the swing of said stop means to a position substantially parallel to the axis of tilt, whereby said stop means when limited in swing by said stop pin may abut against said table to limit the tilt of said fence relative to said table.

2. In a jointer having a table, an adjustable fence movable and tiltable over said table, a tilt plate attached to one end of said fence, the improvement comprising: swingable stop means for limiting the tilt of said tilt plate, a pivot bearing for mounting said stop means on the periphery of said tilt plate, said bearing having an axis substantially radial to the axis of tilt of said tilt plate, a radially extending stop pin on the periphery of said tilt plate co-acting to limit the swing of said stop means to a position normal to the tilt plate whereby said stop means may abut against said table and said stop pin to limit the

tilt of said fence, and means to clamp said tilt plate and fence in position.

3. A stop means according to claim 2 including a set screw at its abutting end.
